CLAIM

The ornamental design for a flexible water container, as
shown and described.

DESCRIPTION

FIG. 1 is a perspective view of a flexible water container showing my new design in use;

FIG. 2 is an enlarged front elevational view thereof;

FIG. 3 is a right side elevational view thereof;

FIG. 4 is a top plan view thereof;

FIG. 5 is a rear elevational view thereof;

FIG. 6 is a left side elevational view thereof; and

FIG. 7 is a bottom plan view thereof.

The broken line showing of a hand and lower arm is for
illustrative purposes only and forms no part of the
claimed design.

FIG. 1

FIG. 2

FIG. 3

FIG. 4

FIG. 5

FIG. 6

FIG. 7
